US0D1096006S

(12) **United States Design Patent** (10) **Patent No.:** **US D1,096,006 S**
(45) **Date of Patent:** **** Sep. 30, 2025**

(54) **PET FEEDER**

(71) Applicant: **SHENZHEN STARISE CREATION TECHNOLOGY CO., LTD**, Shenzhen (CN)

(72) Inventor: **Wenliang Huang**, Shenzhen (CN)

(73) Assignee: **SHENZHEN STARISE CREATION TECHNOLOGY CO., LTD**, Shenzhen (CN)

(**) Term: **15 Years**

(21) Appl. No.: **29/933,850**

(22) Filed: **Mar. 22, 2024**

(51) **LOC (15) Cl.** **30-03**

(52) **U.S. Cl.**

USPC **D30/129**

(57) **CLAIM**

The ornamental design for a pet feeder as shown and described.

DESCRIPTION

FIG. 1 is a perspective view of a pet feeder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the pet feeder that form no part of the claimed design.

1 Claim, 8 Drawing Sheets
